UNITED STATES PATENT OFFICE

2,491,286

VERTICAL ROLLING MILL

John W. Sheperdson and Joseph M. O'Malley,
Worcester, Mass., assignors to Morgan Con-
struction Company, Worcester, Mass., a cor-
poration of Massachusetts

Application June 6, 1945, Serial No. 597,770

1 Claim. (Cl. 80—31.1)

1

This invention relates to mills for rolling metal bars, and more particularly to mills of the type having a pair of vertical rolls which are driven by suitable power-actuated mechanism connected to the lower ends of the rolls.

It is one object of the invention to provide a vertical rolling mill which is so constructed as to facilitate the changing of the rolls.

It is a further object of the invention to provide a vertical rolling mill having simple and effective means for protecting the driving mechanism from scale and water.

With these and other objects in view, as will be apparent to those skilled in the art, the invention resides in the combination of parts set forth in the specification and covered by the claim appended hereto.

Referring to the drawings illustrating one embodiment of the invention and in which like reference numerals indicate like parts:

Fig. 1 is a vertical section through a rolling mill, taken on the line 1—1 of Fig. 2;

Fig. 2 is a plan view of the rolling mill;

Fig. 3 is a section taken on the line 3—3 of Fig. 1;

Fig. 4 is a section taken on the line 4—4 of Fig. 1, with a certain shield removed for clearness of illustration; and

Fig. 5 is an elevation of the rolling mill showing the roll housing being removed therefrom.

The embodiment illustrated comprises a roll housing 10 having upper and lower windows 11 in which are slidably mounted the roll neck bearings 12 of two vertical rolls 14. The housing 10 is releasably secured to a base 15 in known manner by means of slotted studs 17, caps 18 and wedges 19. The base 15 is carried by a foundation 21 shaped to provide a pit 22 within which is located a pinion housing 23 enclosing two roll pinions 25. These pinions are connected by couplings 26 to upright spindles 27 which in turn are connected by couplings 29 to the lower ends of the rolls. These couplings 26 and 29, and the parts which they connect, are formed with loosely interfitting multiple splines to permit telescopic assembly and to transmit a driving torque despite misalignment resulting from roll adjustment. The spindles 27 and the associated couplings may be described as coupling spindles.

Means is provided to support the roll neck bearings 12 against the rolling pressure and to adjust these bearings horizontally within the windows 11, so that the size and position of the roll pass may be controlled. For this purpose the bearings 12 for one roll 14 are engaged by two

manually adjustable horizontal screws 30 mounted in the housing 10 and provided with suitable locknuts 31. The bearings 12 for the other roll 14 are engaged by two horizontal screws 33 mounted in the housing 10 and arranged to be rotated by a suitable power actuated mechanism 34. This mechanism comprises a pair of worm gears 35 rotatably mounted one above the other in a casing 37, with their axes in horizontal alignment with the screws 33. Both of these gears mesh with a horizontal worm 38 located between them and arranged to be driven by an electric motor 39 (Fig. 2). Horizontal shafts 41 extend axially through the gears 35, and suitable clutches 15 42 are provided to connect these shafts with the corresponding gears. The ends of the shafts 41 adjacent the screws 33 are releasably connected thereto by any suitable means, such as the slideable sleeves 44. These sleeves, as well as the adjacent portions of the shafts and screws, may be of square or otherwise non-circular cross-section. Pins 45 may be used to secure the sleeves to the ends of the screws. Upon withdrawal of these pins, the sleeves may be moved along the shafts 41 to disconnect these shafts from the screws 33, as shown in Fig. 5. This will make it possible to lift the housing 10 without disturbing the power actuated mechanism 34.

It is important to retain the spindles 27 and the couplings 29 in their proper positions by supporting them laterally when the rolls 14 are withdrawn from the couplings by lifting the housing 10. For this purpose suitable retaining devices 47 are adjustably mounted on the base 15 for engagement with the couplings. As best shown in Fig. 4, these retainers 47 are forked to straddle the couplings 29, there being two oppositely disposed retainers for each coupling. The retainers 47 are pivotally and slidably mounted on two parallel horizontal rods 48 located at opposite sides of the couplings and carried by brackets 49 secured to the base 15. These parts are so constructed and arranged that the retainers 47 may be swung upwardly and outwardly to the positions indicated by the broken lines in Figs. 3 and 4, so that they will not interfere with the couplings when the mill is in operation.

Means is provided to prevent water and scale from entering the pit 22. For this purpose the base 15 is shaped to provide a trough having a bottom wall 51 which preferably slopes to one side in order that water may be discharged therefrom to a suitable drain (not shown). This wall 51 is provided with a laterally elongated opening 52 through which the spindles 27 extend, this

opening being of sufficient size to permit removal of the spindles 27 and the lower couplings 26 upwardly therethrough. The opening 52 is surrounded by an upstanding flange 53. A rib or baffle 54 is provided on the upper surface of the wall 51 and spaced upstream from the opening 52, this rib being of arcuate shape in plan (as shown in Fig. 4) with its concave side toward the opening, in order to deflect the water stream laterally toward opposite sides of the opening and prevent direct impingement of water on the flange 53. The opening 52 is covered by a plate or shield 56 having a depending marginal flange 57 which overhangs the outer surfaces of the flange 53 and rib 54. This plate 56 has two circular holes 58 therein through which the spindles 27 extend. Each hole 58 is surrounded by an upstanding flange 60 which is surrounded by a depending flange or skirt 61 formed on the coupling 29 thereabove. This provides a very effective seal to prevent water and scale from reaching the holes 58.

The operation of the invention will now be apparent from the above disclosure. The rolls 14 will be driven from a suitable source of power through the pinions 25, couplings 26, spindles 27, and couplings 29, the retainers 47 resting in their outer positions as indicated by the broken lines in Fig. 4. The roll adjusting screws 33 may be actuated by the motor 39 through the worm 38, gears 35, clutches 42, shafts 41 and sleeves 44. To adjust one of the screws 33 independently of the other, it is merely necessary to disengage one of the clutches 42. Any water from the rolling operation will fall into the trough 51 and flow laterally to a drain, the plate 56 and the associated overlapping flange construction preventing the water from reaching the opening 52. When it becomes necessary to change rolls, the operator will swing the forked retainers 47 inwardly to engage the upper couplings 29, as shown in Fig. 4, first moving the retainers along the rods 48 if necessary. The pins 45 will be withdrawn from the screws 33, and the sleeves 44 moved along the shafts 41 out of engagement with these screws. 45

The wedges 19 and caps 18 will then be removed from the studs 17, whereupon the housing 10 and rolls 14 may be lifted from the base 15 by means of a suitable crane sling 63, as shown in Fig. 5. 5 Another housing, with a different set of rolls, may then be lowered into place. During this changing of housings, the retainers 47 will hold the spindle couplings 29 and the spindles 27 in their proper positions. The power actuated roll adjusting mechanism 34 does not need to be disturbed at all. The roll change can therefore be completed very rapidly, and the mill need be shut down only for a comparatively short time.

Having thus described our invention, what we claim as new and desire to secure by Letters Patent is:

20 A rolling mill comprising a supporting base, a roll housing mounted on the base and releasably secured thereto, a pair of vertical rolls mounted 25 in the housing, a pair of roll pinions beneath the base, upright coupling spindles connecting the pinions with the rolls thereabove to drive the same, fork-shaped retaining devices located at 25 opposite sides of the coupling spindles, and means secured to the base to support the said devices for pivotal movement about parallel horizontal axes at opposite sides of the coupling spindles, the said devices being arranged to be swung inwardly about their axes to positions in which they straddle the upper portions of the coupling spindles to support the same laterally when the housing and rolls are lifted from the base.

JOHN W. SHEPERDSON.
